PHONOGRAPH CONSOLE

William B. Donnelly, Syracuse, N.Y., assignor to
General Electric Company

Filed Nov. 12, 1970, Ser. No. 25,942

Term of patent 14 years

Int. Cl. D14—03

U.S. Cl. D56—4

FIG. 1

FIG. 2

FIG. 3

FIG. 4

FIG. 1 is a left side, top and front perspective view of a phonograph console, showing my new design;

FIG. 2 is a front elevational view, the rear being substantially a mirror image thereof;

FIG. 3 is a top plan view; and

FIG. 4 is a side elevational view, the opposite side being substantially a mirror image thereof.

I claim:

The ornamental design for a phonograph console, as shown and described.
